(57) **CLAIM**

The ornamental design for a connector as shown and described.

DESCRIPTION

FIG. 1 is a frontal elevational view of a connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof;

FIG. 10 is a rear, left, and top side perspective view thereof;

FIG. 11 is a frontal elevational view of a connector in an altered configuration showing our new design;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a front, top, and right side perspective view thereof;

FIG. 18 is a rear, bottom, and left side perspective view thereof;

FIG. 19 is a front, right, and bottom side perspective view thereof; and,

FIG. 20 is a rear, left, and top side perspective view thereof.

The broken line showing of the connector is for the purpose of illustrating portions of the article and forms no part of the claimed design.
